UNITED STATES PATENT OFFICE

129,325

DESIGN FOR A STORE FRONT

Joseph S. Dworsky, New York, N. Y.

Application April 12, 1941, Serial No. 100,356

Term of patent 14 years

To all whom it may concern:

Be it known that I, Joseph S. Dworsky, a citizen of the United States, residing at 17 West 71st Street, in the city of New York, county of New York, State of New York, have invented a new, original, and ornamental Design for a Store Front of which the following is a specification, reference being had to the accompanying drawing, forming part thereof.

Fig. 1 is a front perspective view of a store front showing my new design; and

Fig. 2 is a sectional view, on a smaller scale, taken on line 2—2 of Fig. 1.

The left wall of the vestibule in Fig. 1 corresponds to the right wall shown in said figure.

I claim:

The ornamental design for a store front, substantially as shown and described.

JOSEPH S. DWORSKY.
